UNITED STATES PATENT OFFICE.

GEORGE R. CLARK, OF DETROIT, MICHIGAN.

WATER MOTOR.

Application filed August 3, 1921. Serial No. 489,509.

To all whom it may concern:

Be it known that I, GEORGE R. CLARK, a citizen of the United States, residing at Detroit, in the county of Wayne and State of Michigan, have invented certain new and useful Improvements in a Water Motor; and I do hereby declare the following to be a full, clear, and exact description of the invention, such as will enable others skilled 10 in the art to which it appertains to make and use the same.

This invention has relation to certain new and useful improvements in a water motor and has for its primary object the 15 provision of a simple, inexpensive and efficient water motor especially adapted for use in channels or rivers, streams and the like for utilizing economically the motion of the water under conditions adapting the 20 power so derived to be employed for pumping purposes.

The invention has for another object the provision of a water motor of the character stated which may be formed in units suitably coupled together so that the combined 25 power derived from the operation of the various units may be directed to a single shaft, from which the power may be utilized for the purpose intended.

30 The invention has for another object the provision of a water motor of the character stated in which will be included a cylindrical casing mounted in a suitable frame and held stationary therein while the water 35 wheel operating in the casing and consisting of a spindle carrying a volute blade of a diameter corresponding substantially with the interior or bore of the casing, is mounted in suitable bearings carried by the casing so that power may be generated by rotation of the water wheel caused by the 40 water in the stream passing through the casing when the device is positioned properly in the stream.

45 The invention has for a further object the provision of a water motor of the character stated in which the stationary casing will be provided with suitable water directing funnels or flanges to retard the movement 50 of the water longitudinally of the exterior of the casing, so that the force of movement of the water through the casing may be increased, the casing having suitable water exit slots in the rear portion thereof or down 55 stream end of the casing beyond the blade of the water wheel to provide for a more

ready escape of the water from the casing after serving to operate the water wheel.

The invention has for a still further object the provision of a water motor of the character stated in which one or more of the units consisting of the casing and the water wheel may be mounted in a suitable supporting frame and a door provided for the forward or upstream end of each casing to retard or practically eliminate the flow of water through the casing when it is desired to retard or completely stop operation of the water motor.

With the foregoing and other objects in view as will appear as the description proceeds, the invention consists in the novel construction, combination and arrangement of cooperating elements as hereinafter more specifically set forth, claimed and shown in the accompanying drawings forming a part of the present application and in which:

Figure 1 is a side elevation of the improved form of motor,

Figure 2 is a longitudinal sectional view through one of the motor units,

Figure 3 is an enlarged detail sectional view of the bearing mounting for a forward or upstream end of the shaft of the unit,

Figure 4 is a similar view of the bearing mounting for the rear or down stream end of the shaft of the unit, within the casing.

Figure 5 is an enlarged detail sectional view on the plane of line 5-5 of Figure 2 of the drawings.

Figure 6 is an end elevation of a modified form of the invention.

Figure 7 is a fragmentary plan view of a pair of units of the motor, showing the gearing between the same and the power receiving and transmitting shaft.

Referring more in detail to the drawings in which similar reference characters designate corresponding parts throughout the several views, it will be understood that the various units are constructed in the same manner. Therefore, a detailed description of one unit will be sufficient without a detailed description of the construction of each unit of the motor.

Each unit of the motor consists essentially of a cylindrical casing or tube 10 having exterior deflectors 11 and 12 of substantially conical form with the bases thereof forming up-stream casing shoulders 13. The deflectors 11 and 12 are in the form of annular flanges and are located at suitable dis-

tances from the ends of the casing 10, as shown clearly in Figures 1 and 2 of the drawings. The casing is also provided with an inlet water directing funnel 14 and a 5 water wheel operating in the casing and consisting of a spindle 15 carrying a volute blade of a diameter corresponding substantially with the interior or bore of the casing. The blade is designated by the numeral 16 10 and preferably terminates short of the upstream end or even with the end of the casing, as indicated in Figure 2, while the ends of the spindle or shaft project from the ends of the casing 10, as will also be understood 15 by referring to Figures 1 and 2 of the drawings. Suitable collars 16' are secured upon the spindle or shaft 15 at the opposite end of the blade 16 to prevent longitudinal movement of the blades upon the spindle or shaft 20 15, after proper adjustment of the blade upon said spindle or shaft 15.

The forward or up-stream end of the casing or tube 10 is provided with a cut-off gate 17 preferably of rectangular form and 25 adapted to slide in suitable guide brackets 17' upon the sides of the casing or tube 10 at the forward or up-stream end thereof, as shown clearly in Figures 1 and 2 of the drawings. The cut-off gate 17 is provided 30 with a suitable slot 17' extending through a portion thereof to accommodate the spindle or shaft 15. It will also be understood that the cut-off gate 17 may be readily raised by a cable 17' or the like connected with the 35 upper edge thereof.

The casing or tube 10 is shown as being provided near its down stream end with longitudinal spaced slots 18 to form relief outlets and thereby reduce the internal pressure, 40 downwardly or rearwardly of the blade 16 and which internal pressure otherwise would tend to retard the rotary movement of the wheel. This structure may be readily understood by referring to Figure 2 of the 45 drawings.

The spindle or shaft 15 is mounted in bearings 19 and 20 at the forward or up-stream end and the rear or down-stream end respectively of the casing, or tube 10, so 50 that the spindle or shaft 15 may freely rotate with the blade 16 forming the wheel of the water motor. The form of bearing 19 which is employed in the present instance is shown in section in Figure 3 and consists 55 in a substantially frusto-conical bearing member 19' carried by the shaft or spindle 15 and having engaged on the conical seat 19' thereof the bearing balls 19' which also engage the conical seat 19' formed in the 60 bearing sleeve 19' positioned around and spaced from the bearing member 19'. It will be understood that the seats 19' are opposed to one another and the sleeve 19' is surrounded by the collar 19' which is 65 in turn connected with the interior wall

of the casing or tube 10 by suitable supporting arms 19', as will be seen by referring to Figure 2 of the drawings. The sleeve 19' is prevented from moving longitudinally of the shaft or spindle 15, by the end bearing plates 19' which are secured in the opposite ends of the collar 19' and have central openings the walls of which are spaced from the spindle or shaft 15 so as not to interfere with the free rotation of the shaft. 70

The bearing 20 for the rear or down-stream end of the water motor is shown in section in Figure 4 of the drawings and comprises, in the present instance, a rotary bearing member 20' mounted rigidly on the shaft or spindle 15 and having an annular flange 20' adjacent one end with an annular bearing ball groove or runway 20' at one end of the member 20', adjacent the flange 20' while a second annular groove or runway 20' is formed in the member 20' on the outer side of the flange 20' and a spaced distance therefrom, the member 20' being then extended in a reduced form from the groove or runway 20'. The flange 20' extends toward 90 the inner wall of the stationary bearing sleeve 20' which is supported in the rear or down-stream end of the casing or tube 10 by suitable supporting arms 20', as clearly shown in Figure 2 of the drawings. Bearing balls 20' are positioned in the groove or runway 20' forming one seat therefor and also contact with the opposite runway or seat 20' formed in the stationary bearing plate 20' carried in the sleeve 20' adjacent one end 95 thereof and held in position by one of the end plates 20' of the bearing structure 20. The opposite end plate 20' is positioned in the other end of the bearing sleeve 20' and retained in position, the stationary bearing cup 20' which surrounds the small end of the bearing member 20' and has an annular groove or runway 20' cooperating with the runway 20' to form seats for the bearing balls 20'. It will be understood that the 100 bearing plate 20' and the bearing cup 20' are spaced from the bearing member 20'. It will also be understood that the central opening of the bearing plate 20' as well as the central openings of the end bearing plates 20' are of suitable diameter to space the walls thereof from the shaft or spindle 15 and thereby eliminate danger of interference with the free rotation of said shaft or spindle 15.

While the specific construction of the bearings 19 and 20 have been shown and described, it will be understood that these structures may be varied, as desired.

It will also be understood that suitable bearings 21, which are not shown in detail, may be provided on transverse connecting and bracing strips 22 of a supporting frame 23 within which the casing or tube 10 is suspended. These transverse strips 22 may 130

serve to connect and brace the vertical end or corner members 24 of the frame 23 and the shaft or spindle 15 extends through the bearing 21. It will be understood that the 5 frame 23 is preferably of rectangular form and the longitudinal or side strip 25 of the upper portion of the frame may be connected with the upper ends of the corner member 24 as shown in Figures 1 and 6 of 10 the drawings and also connected with said corner members 24 by the inclined bracing frame members 26, as shown clearly in Figure 1 of the drawings. The casing or tube 10 may be suspended in the frame 24 by a 15 plurality of suspending rings 27 connected with the upper portion of the frame 24, as shown at 28 or in any other suitable and well known manner.

The spindle or shaft 16 has its rear or 20 downstream end supported in a suitable bearing 30 which is preferably bifurcated and carried on a supporting arm 29 projecting from the rear or down stream end of the frame 23, as shown in Figure 1 of the 25 drawings. The shaft or spindle 15 carries a drive worm 31 between the arms of the bifurcated bearing 30 and the drive worm 31 is adapted to engage and drive the worm wheel 32 mounted on the upstanding shaft 30 or power shaft 33. As shown in Figure 7 of the drawings, the units of the water motor are preferably arranged in pairs with the shaft or spindles 15 of two units in the same horizontal plane cooperating to drive 35 a single upstanding shaft or power shaft 33. In this arrangement the drive worms 31 of the pair of shafts or spindles 15 are reversed so that both will serve to drive the worm wheel 32 in the same direction. The 40 worm wheel 32 may be securely locked upon the shaft 33 in a suitable and well known manner and this shaft 33 may have its lower end mounted in a suitable bearing 34 formed in the connecting arm 35 extended between 45 the bifurcated bearings 30 for the pair of shafts or spindles 15. This structure may be readily understood by referring to Figure 6 of the drawings which shows two pairs of units connected as described and serving to 50 drive a single power shaft 33.

By referring to Figure 6 of the drawings, it will be seen that four or more of the units may be mounted in a single supporting frame 23 without any material alterations in the construction and operation 55 of the water motor.

While the units have been shown as arranged in horizontal pairs, it will be understood that this may be varied and the units 60 arranged and connected in any suitable manner to provide for the existing conditions under which the water motor is to be employed.

While the preferred embodiments of the 65 invention have been shown and described,

it will be understood that minor changes in the details of construction and arrangement of parts may be resorted to within the scope of what is claimed without departing from the spirit of the invention. 70

What I claim is:—

1. A water motor having a cylindrical casing, means for suspending said cylindrical casing within a stream or water channel, a wheel consisting of an axial spindle carrying a volute blade within said casing, said casing being provided with an exterior flow retarding means, and means carried by said spindle for driving a power shaft. 75

2. A water motor having a cylindrical casing, a wheel within said casing consisting of an axial spindle carrying a volute blade, means for holding said casing stationary, and means carried exteriorly of said casing to retard the flow of water past 80 the same. 85

3. A water motor having a cylindrical casing, a wheel within said casing consisting of an axial spindle carrying a volute blade, means for holding said casing stationary, 90 means carried exteriorly of said casing to retard the flow of water past the same, said last mentioned means consisting of conical projections having their faces directed upstream to present obstructing shoulders, 95 a power shaft, and means carried by said spindle for driving said power shaft. 95

4. A water motor unit having a cylindrical casing, a water wheel mounted therein and consisting of an axial spindle and a volute blade carried by said spindle, said casing being provided near its outlet or downstream end with lateral outlets to relieve the pressure upon the rear end portion of the blade, and a power shaft driving means carried by the rear end portion of said spindle. 100 105

5. A water motor unit having a cylindrical casing, a wheel mounted within said casing and consisting of an axial spindle and a volute blade, said casing being provided near 110 its outlet or down-stream end with lateral relief water discharge openings, and means carried by said casing exteriorly thereof and in advance of said openings to retard the flow of water past said casing. 115

6. A water motor unit having a cylindrical casing, a water wheel within the casing and consisting of an axial spindle and a volute blade carried by said spindle, said casing being provided near its outlet or 120 down-stream end with lateral outlets to relieve the pressure upon the rear end portion of the blade.

7. A water motor unit having a cylindrical casing, a water wheel mounted therein and consisting of an axial spindle and a volute blade carried by said spindle, said casing being provided near its outlet or 125 down-stream end with lateral outlets to relieve the pressure upon the rear end por- 130

- tion of the blade, and said lateral outlets comprising longitudinal slots cut in said casing adjacent the down-stream end thereof.
- 5 8. A water motor unit having a cylindrical casing, a wheel mounted within said casing and consisting of an axial spindle and a volute blade, said casing being provided near its outlet or down-stream end 10 with elongated longitudinal slots to pro-

vide release water discharge openings, and means carried by said casing exteriorly thereof and in advance of said opening to retard the flow of water past said casing.

In testimony whereof I affix my signature 15 in presence of two witnesses.
